METHOD OF COOLING MOLTEN MATERIAL

Edward J. Pranke, Great Barrington, Mass., assignor to E. I. du Pont de Nemours & Company, Inc., a corporation of Delaware

Application October 12, 1931, Serial No. 568,517

7 Claims. (Cl. 62—170)

This invention relates to the cooling of molten material, and particularly to the cooling of molten cyanids, and has for its object the rapid cooling of such material.

5 In dealing with molten material, it is often of primary importance to cool such material as rapidly as possible. Certain molten cyanids, for example, are unstable at elevated temperatures, and in order to avoid decomposition of the product it is necessary to cool it as rapidly as possible to temperatures at which it is stable. Some molten cyanid mixtures, such as those containing large amounts of chlorids, have in the past been cooled by tapping the molten product in thin 10 layers into a mold, or into a receiver from which it is picked up by a rotating water-cooled drum which dips beneath the surface of the molten material. Such a method depends for its success upon the use of a cyanid which will remain stable 15 and fluid in the receiver until it is picked up by the drum.

In U. S. Patents 1,947,570 and 2,004,130, which were issued on my co-pending applications Serial No. 472,482 and Serial No. 623,026, respectively, 20 I have disclosed a number of ways in which an alkali-alkaline earth cyanid, sodium calcium cyanid, which I have discovered, can be prepared. Numerous experiments have shown that this compound, produced in accordance with my said invention, and free of chlorids, is quite stable at the preferred temperature of formation, namely about 1400° C. It is only slightly decomposed at about 1300° C., but is very unstable and decomposes rapidly at about 1250° C., losing free nitrogen at a rapid rate, leaving a pasty mass which does not flow freely below about 1200° C., and in which the percentage of cyanid is greatly reduced. At 200° C., or lower, my product is substantially stable.

40 In order to avoid the decomposition which occurs between 1300° C. and possibly 200° C., but which is most rapid at about 1250° C., I have found that it is necessary to reduce the temperature of the molten cyanid from the preferred temperature of formation of about 1400° C. to less than 200° C. in as short a time as possible.

This cooling can not be satisfactorily accomplished by the method above referred to, because my product will decompose substantially, and become pasty, before it can be picked up by the drum rotating on a horizontal axis.

I have found that the cooling of my product can be conveniently and efficiently accomplished by causing a free, that is, unconfined stream of 50 the molten cyanid, tapped from the furnace in

which it is formed, and without substantial loss of temperature, to impinge upon a surface, preferably metal, moving in relation to the stream in such a way that between the combined force of gravity and the motion of the moving surface the 5 highly fluid, molten cyanid will be spread out in a thin sheet or layer adhering to the surface, by which it is rapidly cooled, after which it may be scraped off in thin flakes.

To provide a suitable cooled surface, I prefer to 10 use a cylindrical iron drum, supplied with cooling water and rotated at a suitable speed, and I incline its axis of rotation, and therefore the angle of its cylindrical surface to the impinging stream of molten cyanid, so as to give the maximum amount of flow downward before chilling occurs. The speed of rotation is such as to give the maximum amount of spreading horizontally, while allowing sufficient time for the layer of 15 cyanid on the surface to cool before the drum 20 makes one revolution and to be scraped off.

For example, in order to cool say 500 pounds of molten product per hour I may use a drum 30 inches in diameter, and 18 inches long, rotated at about 30 revolutions per minute, and provided 25 with a scraper to remove the chilled product after it has traveled nearly a revolution. The drum is placed so that the stream of molten cyanid, issuing from the tap hole of the furnace, will fall upon the upper part of the cylindrical 30 surface tilted back say 30 degrees from the vertical. Gravity will then carry the material down towards the lower part of the cylindrical surface while the horizontal motion of the revolving surface will spread the molten product horizontally, 35 thus giving the desired amount of spreading over the cooled surface.

Instead of utilizing a rotating drum, I may accomplish the desired result by causing a metal band or endless belt to move in a similarly inclined 40 plane and in a horizontal direction, on which belt the stream of molten cyanid coming from the furnace impinges and spreads. The molten material may impinge upon one side of this belt, while the other side is cooled in any convenient 45 manner, as by a water spray.

The accompanying drawing illustrates apparatus suitable for the practice of my process. In the drawing:

Fig. 1 is a diagrammatic side elevation showing 50 an inclined rotating cooling drum;

Fig. 2 is a diagrammatic side elevation showing an inclined endless cooling belt;

Fig. 3 is a diagrammatic rear elevation showing 55 an endless cooling belt.

Referring to the drawing, and particularly to Fig. 1, 1 indicates an electric furnace or other receptacle containing molten cyanid or other fluid material which it is desired to cool. The furnace is provided with a spout or other outlet 2 from which the fluid contents of the furnace may be removed in a stream 3. 4 indicates a rotating double-walled cylinder or drum, of metal or other suitable material. This drum is mounted in an adjustable frame 5 by means of bearings 6. Water or any other suitable cooling medium may enter the interior of the drum 4 between the walls thereof by means of the inlet 7, leaving by the outlet 8. The drum may be rotated in any suitable manner, as, for example, by means of the motor 9 and gearing 10.

The drum is provided with a scraper 11, which may be adjustable with relation to the drum surface, and which removes the cooled and solidified cyanid or other material from the surface of the drum. The rotation of the drum is in the direction of the arrow in Fig. 1.

It will be noted that the drum is mounted at a substantial angle from the horizontal so that as the stream 3 impinges upon the upper part of the drum, the molten cyanid will be spread in a thin layer upon the surface of the drum by the combined effect of gravity and the relative lateral movement of the drum surface and the stream.

Referring to Figs. 2 and 3, 15 represents an endless belt of metal or other suitable material, substantially inclined from the horizontal and moving in a lateral direction relative to the stream 3, around roller 16, in the direction of the arrows. The material to be cooled impinges upon the outer side of the belt and the inner side of the belt is suitably cooled, for example by means of a water supply 17 terminating in a plate or spray connection 18. The water sprayed on the inner side of the belt may be collected in the trough 19 provided with a drain 20.

A scraper 11 is provided, which removes the cooled and solidified material from the surface of the belt, when it may be collected in a suitable receptacle.

I have described my improved method of cooling with regard to its application to molten cyanid, because it is especially advantageous in such case, where rapid cooling is desirable and not obtainable by methods heretofore known.

In the appended claims the word "lateral" is employed to designate a direction toward the side or from side to side, as distinguished from a strictly vertical direction.

Those skilled in the art may vary the details of my invention without departing from the spirit thereof.

I claim:

1. The process of rapidly cooling molten cyanid which consists in tapping a stream of the molten cyanid from a furnace, causing it to impinge immediately and without substantial loss of tem-

perature upon a cooled surface substantially inclined from the horizontal and spreading the molten cyanid thereon by moving the surface laterally relative to the said stream, whereby a thin layer of the cyanid remains in contact with the surface until substantially cooled.

2. The process of rapidly cooling molten cyanid which consists in causing a stream of such cyanid to impinge and spread in a thin layer upon a cooled surface inclined from the horizontal and moving in a lateral direction relative to the stream at the point of contact therewith, and after spreading to remain in contact with such surface until substantially cooled.

3. The process of rapidly cooling molten cyanid which consists in causing a stream of such cyanid to impinge and spread in a thin layer upon the surface of a cooled cylinder rotating about an axis substantially inclined from the horizontal, and after spreading to remain in contact with such surface until substantially cooled.

4. The process of cooling molten cyanid which comprises spreading the molten cyanid in a thin film on a cooling surface by causing a stream of such material to impinge upon such surface substantially inclined from the horizontal and moving in a substantially horizontal direction at the point of contact, the cyanid remaining in contact with the surface until substantially cooled.

5. The process of cooling molten cyanid which comprises causing a stream of such material to impinge upon a cooled surface inclined from the horizontal and moving across the median vertical plane of the said stream, and to spread upon such surface by the combined effect of gravity and the said movement of the surface, and after spreading to remain in contact with such surface until substantially cool.

6. The process of cooling molten cyanid which comprises causing a stream of such material to impinge upon a cooled surface inclined from the horizontal and moving in a lateral direction relative to the stream at the point of contact therewith, and to spread upon such surface by the combined effect of gravity and the said lateral movement of the surface relative to the stream, and after spreading to remain in contact with such surface until substantially cooled.

7. The process of cooling molten material which comprises causing a stream of such material to impinge upon a cooled surface inclined from the horizontal and moving in a lateral direction relative to the stream at the point of contact therewith, and to spread upon such surface by the combined effect of gravity and the said lateral movement of the surface relative to the stream, and after spreading to remain in contact with such surface until solidified, said cooled surface being inclined at a sufficient angle to cause a substantial downward flow of the molten material thereon before said material becomes solidified.

EDWARD J. PRANKE.
